UNITED STATES PATENT OFFICE.

HERBERT O. ROCKWELL, OF NEW BRITAIN, CONNECTICUT, ASSIGNOR TO THE BRADY ELECTRIC & MANUFACTURING COMPANY, OF NEW BRITAIN, CONNECTICUT, A CORPORATION OF CONNECTICUT.

CABLE SUPPORT.

Application filed July 23, 1921. Serial No. 486,945.

To all whom it may concern:

Be it known that I, HERBERT O. ROCKWELL, a citizen of the United States, and a resident of New Britain, county of Hartford, State of Connecticut, have invented certain new and useful Improvements in a Cable Support, of which the following is a specification.

The object of the invention is to produce a cable support having features of novelty and advantage. Supports of this sort are designed particularly for use with flexible cables and to permit of readily drawing a cable through the support or of readily attaching the support to a cable already strung, and are preferably equipped with a roll support in the nature of a grooved wheel of insulating material to permit free movement of the cable. These supports are intended for attachment to sides of buildings, to poles, rafters, etc., by means of a support in the nature of a lag screw. In the present invention the holder itself is readily separated from the lag screw and provision is made for the use of the ordinary lag screws as are customarily found on the market, means being provided for permitting the attachment of the holder to the supporting screw.

In the accompanying drawings—

Fig. 1 is a side view of the holder shown in place,

Fig. 2 is an end view of the same, and

Fig. 3 is a detail view of the holder properly removed from the supporting lag screw and showing the method of connecting the two parts, i. e., the holder and lag screw.

Referring to the drawings, *a* denotes a lag screw of the ordinary type readily found on the market and which, as shown, usually has a square head. *b* is a clip apertured to receive the lag screw and with its two ends folded up against the square head of the lag screw in such a manner that the lag screw does not turn in the clip. The ends *c* of the clips which project beyond

the head of the lag screw are bent into contact to receive the arms of the holder indicated generally at *e*. This holder comprises a spindle 5 upon which is mounted a 50 groove wheel 6 of insulating material and on the projecting ends of the spindle are rotatably mounted the complementary arms 7, 7, with oppositely inturned ends 8, 8, which preferably are shaped to overlap and 55 fit together to form the loop which is indicated at 9 in Figure 1.

The holder can be readily disassembled from the lag screw clip by tilting it to one side and passing it through the aperture 60 until one of the arms 7 can be disengaged, then by tilting it in the opposite direction until the other arm 7 is disengaged. By the use of the clip *b* an ordinary lag screw can be utilized. The clip can be used 65 either for the application of a wrench or some other convenient means for positioning the lag screw in the support, and the aperture in the projecting contacting ends provides the means to receive and retain 70 the holder.

I claim as my invention—

In a device of the character described, a lag screw with an angular head, a clip apertured to receive said lag screw and fitting 75 against the outer side of the head, said clip then being bent against opposite sides of the head to prevent relative rotation therebetween, the ends of said clip projecting beyond said head and being bent into contact and apertured, and a holder comprising a spindle, an insulating roller mounted thereon, arms, at least one of which is rotatably mounted, at either end of the spindle at either side of said roller, said arms 80 having complementary hooked shaped ends adapted to be passed through the apertures on the end of said clip, said ends adapted to be moved to overlapping position to form a loop to support the ends of said 85 spindle from said clip.

HERBERT O. ROCKWELL.
